UNITED STATES PATENT OFFICE

160,927

VALVE OPERATING SPRAY NOZZLE CAP UNIT

John C. Crowley, Willoughby, Ohio

Application October 26, 1949, Serial No. 5,710

Term of patent 14 years

(Cl. D83—1)

To all whom it may concern:

Be it known that I, John C. Crowley, a citizen of the United States and a resident of Willoughby, in the county of Lake and State of Ohio, have invented a new, original, and ornamental Design for a Valve Operating Spray Nozzle Cap Unit, of which the following is a specification, reference being had to the accompanying drawings, forming a part hereof.

In said drawings, Fig. 1 is a front perspective view of a valve operating spray nozzle cap unit, showing my new design; Fig. 2 is a top plan view

of said device; Fig. 3 is a front elevational view; Fig. 4 is a rear elevational view; and Fig. 5 is a bottom plan view. In all views, the salient features of the design reside in those portions thereof shown in full lines.

I claim:

The ornamental design for a valve operating spray nozzle cap unit, as shown and described.

JOHN C. CROWLEY.
